UNITED STATES PATENT OFFICE.

STERLING W. WARNER, OF CRANFORD, NEW JERSEY, ASSIGNOR TO THE AEOLIAN COMPANY, A CORPORATION OF CONNECTICUT.

PERFORATED-MUSIC-DUPLICATING MACHINE.

Application filed October 9, 1920. Serial No. 415,846.

To all whom it may concern:

Be it known that I, STERLING W. WARNER, a citizen of the United States, and a resident of Cranford, Union County, and State of New Jersey, have invented certain new and useful Improvements in Perforated-Music-Duplicating Machines, of which the following is a specification, reference being had to the accompanying drawings, 10 forming a part thereof.

My invention relates to pneumatic duplicators for perforated music rolls particularly of the type in which a master roll is carried over a tracker bar and the mechanism connected thereto rapidly and faithfully reproduces the original or master roll in a plurality of copies.

An object of the invention is to provide a compact, reliable and efficacious apparatus 20 for faithfully and correctly duplicating the original master roll in one or more copies.

A further object is to provide quick acting, automatic means for the purpose described.

25 Other objects relate to the simplicity of the mechanism, durability of construction and responsiveness of action of the parts, and the accuracy of duplication of the master sheet.

30 With the foregoing and other objects in view, which will become apparent as the description proceeds, my invention resides in the combination and arrangement of parts and in the details of construction, with 35 due regard for mechanical equivalents, described in the specification, illustrated in the drawings, and particularly pointed out in the appended claims, it being understood that I do not limit myself to the precise embodiment of the invention herein disclosed and changes can be made within the scope 40 of what is claimed without departing from the spirit of the invention. I therefore intend no limitations other than those imposed by the appended claims.

In the drawings:

Figure 1 is a diagrammatic sectional elevation illustrating a machine embodying my invention.

45 Figure 2 illustrates more particularly a roll driving arrangement of the device of Fig. 1.

Figure 3 illustrates in sectional plan an arrangement of valves in the device of 50 Fig. 1.

Figure 4 represents an elevation of the two tiers of the valve chest, shown in Fig. 3.

Figure 5 is a transverse sectional elevation on the line 5—5 of Fig. 3, on a larger scale.

Figure 6 is a detail sectional elevation to a larger scale of a perforating arrangement shown in Fig. 1.

Figure 7 is a detail of one of the punch connections.

Figure 8 is a plan view, partly in horizontal section, of some of the punch-pneumatics and their valves, some of the punches being also shown in horizontal cross section.

Figure 9 is an elevation as looked at from 70 the right in Fig. 6 or Fig. 8.

Figure 10 is a vertical sectional detail at right angles to Fig. 6, through the punch guide-plates, the die-plate and its supporting cylinder.

Figure 11 is a face view of a type of 75 double duct tracker bar used.

Figure 12 is a diagrammatic elevational layout of a plurality of the perforating punches.

Figures 13, 14 and 15 are enlarged detail views illustrating progressive positions of a perforation in a master roll passing over one of the double ducts of the tracker bar.

Similar reference characters refer to 85 similar parts throughout the several views.

In Figures 1 and 2, 10 represents a roll to be duplicated, hereinafter called a "master" roll, the perforated sheet of the roll, under proper tension, passing over a double duct 90 tracker bar 9 (compare Fig. 11) by means of which the operation of the copying device is controlled. The sheet then passes between drive rolls 8, and 5, which gives motion to the sheet, and to the take-up roll 95 7. The take-up roll may be driven by a chain or belt 6. A series of drive rolls 5, 5 for the copies are geared together, with the master drive roll 8 to give corresponding speed of motion to the sheets 4, 4 of 100 the rolls to be perforated and the sheet of the master roll 10.

Blank sheets 4, 4 in any number desired pass on a guide-way 3, over a punch guide-plate 2 and under a die-plate 61, where they 105 are perforated, as will be described, then separate, singly or in groups, to pass between various drive rolls 5, 5 already spoken of and are discharged over the plates 1, 1, to be rewound.

The tracker bar 9, as illustrated (Fig. 11) has a double row of ducts, upper ducts 9^a and lower ducts 9^b, preferably of a rectangular shape as illustrated in Figs. 13, 14, 5 and 15. A single pair of upper and lower ducts correspond to a single note, and usually, for a piano-roll, the tracker bar comprises from 80 to 88 of the double ducts, with a number of extra double-ducts at 10 either end and corresponding to the expression perforations for pedals, dynamics, etc., in the player piano music roll or for other purposes.

In Fig. 1, tubes 20, 20^a, lead from the 15 double-ducts 9^a and 9^b for each note and expression device. These tubes pass to a valve chamber 19 (Figs. 1, 3, 4, 5) each tube 20 communicating with a duct 18 (Figs. 3 and 5) and the other 20^a with a corresponding duct 18^a.

Each duct 18, 18^a leads under a corresponding pouch 17, 17^a (Fig. 5) on which rests a valve as 16, 16^a in a suction chamber b above which are ducts a communicating with tubes 15 which in turn are connected with ducts c (Figs. 1, 6) in the punch pneumatic valve casing 14. Bleeds 21, 21^a (Figs. 3 and 5) connect each duct 18, 18^a with the suction chamber b.

30 The control of each tube 15 is effected by a slide valve 13 (Fig. 6) having a passage 32 therethrough. The operation of each valve 13 is by a rod 12 (Figs. 6 and 9) attached to the vibrating boards 11 of the 35 pneumatics 30.

Each pneumatic 30 communicates by a passage 29 (Fig. 6) with a valve chamber 28 in which a valve 27 controls a passage 26 to the atmosphere and a passage 25 to a 40 suction chamber 24, exhausted through pipe 40, each valve 27 being operatively supported on a pouch 23. These pouches 23 separate the suction-chamber 24 and the ducts c, previously mentioned. A bleed hole 22 45 (Figs. 6 and 8) connects each duct c with the suction chamber 24.

Both chambers b and 24 are normally suction or vacuum chambers, communicating by pipes 39, 40 (Fig. 1), respectively, with 50 pipes 37, 38 leading to a main suction pipe 36. Space d (Fig. 5) is open to the atmosphere; and when the valves 16, 16^a, are raised, as shown in the upper part of Fig. 5, ducts a likewise communicate with the 55 atmosphere through the passages controlled by the valves 35, 35^a.

It will be understood that each double duct 9^a, 9^b of the tracker bar is connected by a pair of tubes 20, 20^a to valve devices similar to the ones described so that each double tracker-duct controls the vibratory operation of a single punch operating pneumatic 60 30 as follows:

In Fig. 13 it is assumed that a single perforation in the master sheet has reached 65

the position where only duct 9^a of one of the double ducts is uncovered. This permits air to enter through tube 20 to the duct 18 (Fig. 5) the valves 16, 16^a, being normally in the lower position as shown in the 70 lower valve chest of Fig. 5. This normal position of the valves is maintained when the tracker bar ducts are covered by reason of the ducts 18, 18^a being evacuated through the bleeds and bleed passages 21, whereupon 75 the atmospheric pressure on the valves forces them downward into the position shown in the lower valve chest.

By the admission of air to the duct 18 as 80 by uncovering the duct 9^a, the valve 16 is raised to the position shown in the top chest of Fig. 5, the atmospheric pressure under the diaphragm 17 overcoming the reduced pressure in the suction chamber b above the 85 diaphragm.

The aforesaid raising of the valve 16 admits atmospheric air to the duct a (Fig. 5) past the valve 35, a portion 34 of said valve 16 cutting off communication of the duct a with the suction chamber b. However, this 90 air is insufficient to raise the pouch 23 and valve 27 (Fig. 6) because the arrangement is such that the air admitted by the valve 35 is not so great in amount but that it can be and is exhausted into the chamber b past 95 the valve 34^a (which under the supposed conditions is in its lowered position) without, therefore, being able to affect the exhaust condition under the pouch 23 (Fig. 6) to raise said pouch. In other words, the 100 valve 27 remains down as in Fig. 6 with its punch operating pneumatic 30 on atmosphere and therefore out of operation.

When, however, said assumed single perforation of the master sheet has travelled 105 further to the position shown in Fig. 14, it uncovers also the second (9^b) of the tracker ducts, whereupon the air admitted through the duct 18^a (Fig. 5) raises the other pouch 17^a and the second valve 16^a—35^a and closes 110 34^a. At this time the exhaust chamber b is completely cut off from the duct a, tube 15 and duct c under the related pouch 23 (Fig. 6); and instead only atmospheric air is now admitted under said pouch by 115 way of the two open valves 35—35^a. The result is that said pouch is immediately raised and in turn lifts the valve 27.

This lifted valve 27 thereupon seals the atmospheric port 26 and opens a port 25 connecting the related punch-operating pneumatic 30 with the suction chamber 24. Thereupon the movable board 11 of said pneumatic is immediately depressed and drives the related punch 33 up through the blank 120 sheet or sheets 4 to cut a single perforation therein corresponding to the assumed single perforation in the master sheet.

This movement of the movable board 11 depresses the rod 12 attached thereto (Figs. 130

6 and 9), said rod adjustably supporting a slide valve 13. Through the slide valve 13 is a passage 32 registering between the tube 15 and the duct *c* when the pneumatic is 5 in normal open position. On depression of the rod 12, the motion is communicated to slide valve 13 and the passage 32 is removed from registering position until the duct *c* is completely shut off from the tube 15 by 10 the solid portion of the valve 13.

Immediately the air in duct *c* which held up the pouch 23 and valve 27 is exhausted through the bleed and bleed-passage 22 (Fig. 6) into the suction chamber 24 and a 15 relative vacuum is established below the diaphragm 23 whereupon the valve 27 is again depressed, the suction passage 25 closed and atmospheric air is again admitted through passage 26 to the interior of 20 the pneumatic 30. This together with the action of the resilient member 49 results in said pneumatic opening again to the position shown in Fig. 6, the valve passage 32 again registering between the given pipe 15 25 and duct *c*.

This withdraws the punch which does not again operate because meanwhile the assumed single perforation in the master sheet 10 has passed beyond duct 9^a (Fig. 15) and 30 said duct is closed, only the duct 9^b being open. The result is that the air in tube 20 and duct 18 is quickly exhausted through its bleed 21 (Fig. 5) the pouch 17 drops, and the valve 35 closes again and opens 35 valve 34. The suction chamber *b* now draws into itself the atmospheric air which is being admitted to the duct *a* (Fig. 5) by the open valve 35^a and further immediately exhausts the pipe 15. In other words, there 40 is now no atmospheric air on the pipe 15 necessary to operate the pouch 23 (Fig. 6) and, therefore, said pouch remains down and so keeps its punch-pneumatic 30 out of operation.

45 From the foregoing it will be seen that my described machine produces the desirable result that a single perforation in the master sheet automatically reproduces itself as a single perforation in the copies, the 50 single punching operation taking place at the moment when both of the tracker ducts 9^a and 9^b are opened as in Fig. 14 by the master perforation; and not occurring before that as when only 9^a is open as in Fig. 55 13, nor later as when only 9^b is open as in Fig. 15.

In the event of a slot in the master sheet (as distinguished from a single perforation) 60 passing over any of the double ducts 9^a, 9^b, the first effect is to depress the given bellows board 11 and punch as in the case of a single perforation already described. The passage through the related valve 13 (Fig. 6) is closed, the related duct *c* is 65 evacuated as before explained and its valve

27 opened to atmosphere, the member 11 restored and the duct thereby reconnected with the tube 15 through the passage 32 in the valve 13.

The tracker bar ducts being still uncovered by the slot in the master sheet and the valves 35, 35^a (Fig. 5) being still open, air again rushes into said duct *c*, valve 27 is again lifted and the pneumatic 30 again collapsed to force the punch through the 75 blank sheets 4, valve 13 again closing the passage to the duct *c*. This cycle continues, the given punch 33 rapidly vibrating so long as the corresponding tracker ducts 9^a, 9^b, are open to air through the supposed slot 80 in the master sheet. This produces a plurality of longitudinally disposed perforations which may overlap to make a slot in the blanks 4, 4 corresponding in length with the slot in the master sheet. 85

In the same manner beyond each edge of the master sheet, there is a continuously exposed double tracker-bar duct 9^a, 9^b, whose related punches 33^a (Fig. 12) therefore vibrate continuously and trim the blanks 4 90 to the desired width as they pass over the punches.

It will be understood, of course, that for each double tracker-bar duct there is a complete unit as above described to actuate its 95 related punch 33.

The general frame of the mechanism has horizontal main members 60, 60, (Fig. 1) uprights 59, 59, and transverse supporting channels 58, 58, on which the valve chests 100 14, 14 and 19, 19, are supported, in a plurality of tiers. The valve chests 14, 14 are opposed and staggered (Figs. 1 and 8) to bring all the punches 33, 33 in a single row. Each tier of the valve chests 14 and punch-pneumatics 30 is slightly offset, laterally 105 from the tier above, preferably the distance between adjacent tracker bar ducts, so that the punches 33, 33, 33^a (Fig. 12) will be spaced apart a distance corresponding to 110 the transverse spacing of the tracker bar ducts. Adjacent units of the same tier are spaced equally, the punch operating levers of those units on the near side of the row of punches being shown solid in Fig. 12 and 115 on the far side open. As in the diagram five tiers are indicated, the distance between adjacent punch rods, 33, 33 on the same tier is five times the transverse spacing of adjacent tracker bar ducts. 120

On each valve-casing 14 are brackets 57, one for each pneumatic 30 to support the fixed board 56 thereof and to which the movable board 11 is hinged at 55. (Fig. 6.)

A punch-operating lever 54 is affixed to 125 each moving board 11 and a punch 33 is pivotally attached thereto by the screw-threaded lower end 53 of the punch being screwed into the rotary plug 52 (Figs. 6 and 7) extending across a fork in the end of said 130

lever 54. Each punch is screwed down to a shoulder and so cannot accidentally turn or twist. As these parts are rather small and difficult to readily align for threading purposes, the entering end 51 of the punch is of the diameter of the root of the thread 53 and brought substantially to a tapered point. This end 51 of the punch can be therefore readily introduced into the opening of the transverse plug 52 and the thread 10 will automatically align itself.

The motion of the movable boards 11 of the pneumatics downwardly, and hence the punching stroke of the punches 33, is limited by an adjustable horizontal rail 46 (Figs. 6 and 8) supported over the levers 54 on rods 48, the lower ends of the rods screw into the channel 50 and their upper ends screw oppositely into the rail 46, the blocks 47 on the rods forming convenient means for turning them to adjust the height of the rail.

The motion of the boards 11 in the other direction, viz., on the withdrawal stroke of 25 the punches 33, is limited by adjustable stop 44 (Figs. 6 and 9) one for each pneumatic, mounted each in a tube 43 which itself has a further adjustment where it is supported on the valve chest 14, and is held 30 by a set screw 42.

A spring 49, attached to each lever 54, pulls a lug 41 (Fig. 6) on each board member 11 against its stop 44 on the withdrawal stroke of its punch 33, and the tension of 35 said spring is adjustable as by a nut 45 threading on the closely wound spirals of said spring, the wire of the spring itself thus forming the thread for the nut.

Each punch 33 passes through a guiding 40 bearing 70 in a plate 69 on a frame 68, the whole being vertically adjustable as by the screws 67, 67 and 66 (Figs. 6 and 10) on each side of the frame, the former 67, 67 abutting against a plate 65 affixed to the upper horizontal main members 60, and the latter 66 taking in a threaded opening in 45 said plate to affix the frame 68 to the members 60.

Another guide plate 2 carried by the 50 frame 68, is perforated as at 64, 64, to guide the punches, these perforations through which the punches pass being in a single line and spaced transversely equal to the transverse spacing of the tracker bar ducts 55 9^a, 9^a, or 9^b, 9^b.

Above this plate 2 is an exhaust cylinder 63 held in the upright members 68^a, 68^a of the frame 68 as by a set screw 62 at each 60 end passing through the cross piece 68^b, (Figs. 6 and 10), said set screws 62 clamping the cylinder 63 over the plate 2 (Fig. 10).

Set in the wall of the cylinder 63 with a dove-tail joint (compare Fig. 6) is a die 65 plate 61 perforated as at 70, 70 in line with

perforations 64, 64 in the guide plate 2, the plate 61 being spaced from plate 2 to provide a passage 71 for the music paper blanks, 4, 4 to pass through to be perforated. (Figs. 6 and 10.)

A longitudinal slot 72 (Fig. 6) in the cylinder connects the interior of the cylinder with the perforations 70, 70 of the plate 61. A suction pipe 73 (Fig. 10) connects the interior of the cylinder with the air exhausting system of the machine and removes the punchings by suction from the interior of the cylinder 63 into which they are forced by the punches 33, 33, through the inwardly enlarging openings 70' and the 80 slot opening 72.

The plate 2 is set in a transverse opening in the guide 3 (Figs. 1 and 6) and below the level of the approach and discharge portions of the guide 3, permitting the face 85 of the die-plate 61 to be also below said level, the face of the guide 3 being sloped to meet the face of the punch plate 2. In this way a single blank or a number of blanks passing through the slot 71 are held 90 against the bottom of the die-plate 61 by the feeding tension, and therefore permit the holes punched by the punches 33 to be accurate and clean.

When the punches 33, require sharpening, the vertical adjustment, already mentioned, of the frame 68 and the members carried thereby, accomplished by the manipulation of screws 66, 66, and 67, 67, permits the plate 2 to be lowered to cause the 100 punches to project above it sufficiently to be sharpened conveniently in situ, the die-plate 61 and cylinder 63 having of course been first removed.

Obviously, changes can be made in the 105 above at present preferred embodiment of my invention without departing from the essence thereof and which will still come within the spirit of said invention and of the annexed claims.

Having thus set forth my invention and the principle thereof and a manner of applying that principle, what I claim is:—

1. In a device of the character described, control mechanism comprising a tracker bar 115 having double ducts, perforating mechanism, and pneumatically operative actuating means for said perforating mechanism comprising a control valve responsive to the control of one of said double ducts and actuated through the control of the other of said ducts.

2. In a device of the character described, a tracker bar having double ducts, and pneumatically operated, perforating mechanism 125 operative when both of said double ducts are uncovered, and pneumatically operated means acting individually to render said mechanism inactive with either one of said ducts covered.

3. In a device of the character described, pneumatically operated perforating means, a valve controlling said means, a tracker bar having double ducts, a valve co-acting with each duct and controlling the operation of said first named valve.
4. In a device of the character described, a pneumatically operated perforating means comprising a fixed member, a movable member, and adjustable means to limit the motion of said movable member, a valve to control the operation of said movable member, and means to operate said valve, said last named means comprising a plurality of valves, one of said valves being actuated by said movable member.
5. In a device of the character described, a plurality of perforating devices, a plurality of valve chests, a tracker bar having a plurality of double ducts, a double connection from each of said valve chests to a co-operating pair of said ducts, a connection from each of said valve chests to a cooperating perforating device, and means for individually controlling each of said latter connections whereby each pair of said ducts control one of said perforating devices.
6. In a device of the character described, in combination, a tracker bar having a plurality of double ducts, means to pass a perforated master sheet over said tracker bar to open and close said ducts, a plurality of pairs of valves, the valves of each pair adapted to communicate individually and directly with an exhaust chamber, a connection from each duct to a valve, a plurality of pneumatically operated perforating mechanisms, a control valve for each mechanism, and a connection from each control valve to a pair of the first mentioned valves.
7. In a device of the character described, in combination, a punch, actuating means for said punch comprising a pneumatic, means to admit air to said pneumatic, means to remove air from said pneumatic, a control valve controlling both said means, and a valve actuated by said pneumatic to control the action of said control valve.
8. In a device of the character described, a valve chest, a pair of valves therein, an actuating connection to each of said valves, a perforating mechanism, a passage from said valve chest to said perforating mechanism, and means to block said passage.
9. In a device of the character described, a valve chest, a plurality of valves therein, a suction chamber in which said valves are arranged, actuating means for each of said valves, a passage controlled by the action of both said valves, and means to block said passage.
10. In a device of the character described, a perforating mechanism, a control valve therefor, a perforated master sheet moving device, a tracker bar over which said master sheet moves, a plurality of double ducts in said tracker-bar responsive to the perforations of said master-sheet, a valve chest, a pair of valves therein connected with a pair of said ducts, means to actuate one of said valves on uncovering one of said ducts, means to actuate the other of said valves on uncovering the other of said ducts, and means whereby the operation of both said valves actuates said perforating mechanism.
11. In a device of the character described, a plurality of perforating mechanisms each comprising a pneumatic, a control valve, an actuating pouch chamber for said valve, means to admit air to said chamber, and means actuated by said bellows to block the admission of said air.
12. In a device of the character described, a perforating mechanism comprising a pneumatic, a control valve, an actuating pouch chamber of said control valve, means to individually and directly admit air through a plurality of ports to said chamber comprising a plurality of valves, and separate control means for each of said valves.
13. In a device of the character described, a pneumatically operated perforating mechanism, means for the initial admission of air to increase the responsiveness of said mechanism, and means for the final admission of air to actuate said mechanism.
14. In a device of the character described, a pneumatically operated perforating mechanism, comprising a punch actuating device, a control therefor, means for the initial admission of air to increase the responsiveness of said mechanism, means for the final admission of air to actuate said mechanism, and means whereby the continuous admission of air to said mechanism may be rendered intermittent to said punch actuating device control.

Signed at Garwood, in the county of Union and State of New Jersey, this 6th day of October A. D. 1920.

STERLING W. WARNER.
